INVENTOR.
GEORGE FELIX DE GRASSE,
BY Graham & Harris

ATTORNEYS.

UNITED STATES PATENT OFFICE.

GEORGE FELIX DE GRASSE, OF LOS ANGELES, CALIFORNIA.

TILTING BED.

1,393,885.

Specification of Letters Patent. Patented Oct. 18, 1921.

Application filed December 11, 1920. Serial No. 429,928.

To all whom it may concern:

Be it known that I, GEORGE FELIX DE GRASSE, a citizen of the United States, residing at Los Angeles, county of Los Angeles, 5 and State of California, have invented a new and useful Improvement in Tilting Beds, of which the following is a specification.

My invention relates to beds which are designed to tilt up on edge against a wall 10 when not in use.

The principal object of the invention is to provide a bed which is very stable when in position for use but which can be readily swung up into the raised position by the expenditure of very little strength.

A further object of the invention is to provide a bed of very simple construction in which a conventional type of mattress and spring may be used.

20 Referring to the drawing which is for illustrative purposes only,

Figure 1 is an end view of the bed in position to be used.

Fig. 2 is an end view of the bed in position to be tilted.

Fig. 3 is an end view of the bed in the position it assumes while being tilted.

Fig. 4 is an end view of the bed in its raised position.

30 Fig. 5 is a plan view of the bed in position to be used.

In the form of the invention illustrated, 11 is a bed body which may contain the usual springs or other structure. Pivoted upon a 35 pin 12 near the inner corner of the bed is a pair of inner legs 13 which are pivoted at 14 to floor plates 15. Pivoted on pins 16 near the outer edge of the bed is a pair of outer legs 17 which can be pulled up against the 40 bed in the direction of the arrow A from the position shown in Fig. 1 but which are very rigid against movement in the opposite direction. The legs 17 are provided with friction reducing means such as the wheels 45

18. Pivoted on pins 20 between an axis 21 passing through the center of gravity of the bed and its end, and parallel with its sides is a pair of balanced props 22, the props assuming the position shown in the drawing 50 due to gravity. These props are mounted very loosely so they will always hang vertically. Pivoted at 25 on the floor plate 15 are braces 26.

The method of operation of the invention 55 is as follows:

To tilt the bed from the position shown in

Fig. 1, it is pulled outwardly in the direction of the arrow B until it assumes the position shown in Fig. 2 in which the balance props 22 rest upon the floor and the legs 13 and braces 26 assume the position shown in that figure. The balance props being relatively near to the center of gravity, it is very easy to lift the bed in the direction of the arrow C into the position shown in Fig. 65 3 in which the corners of the bed rest on the floor and the weight may be shifted from the balance props 21 to the bed proper. By continuing to lift and push the bed, it swings about the corner in contact with the 70 floor and assumes the position shown in Fig. 4, adjacent to the wall 35 being slightly separated therefrom to allow a space for the storage of bed clothes, etc. The weight of the leg 17 causes the leg to fall over into the 75 position shown in Fig. 4, the balance props 21 also assuming the position shown in that figure.

If, now, it is desired to move the bed from the position shown in Fig. 4 to the position 80 shown in Fig. 1, it is pulled outwardly in the direction of the arrow D from the position shown in Fig. 4, the legs 17 and the props 21 remaining vertical and the props 21 finally striking the floor in the position 85 shown in Fig. 3. It is then possible to lower the bed into the position shown in Fig. 2 without effort, the outer legs 17 finally taking a portion of the weight in the position shown in Fig. 2. By pushing the body 11 90 toward the wall 35, the bed moves from the position shown in Fig. 2 into the position shown in Fig. 1, the braces 26 engaging the legs 13 under the pins 12 and preventing any further movement of the bed toward the 95 wall. When in this position, the bed is very rigid and there is no danger of its automatically folding up on its own account.

I claim as my invention:

1. In a bed, the combination of: a body; 100 outer legs supporting said body near one edge thereof; inner legs wholly supporting the other edge of said body near the other edge thereof with the bed in its usable position; balance props secured to said body between said inner legs and the center of gravity of said body; and means for shifting the weight of said body from said inner legs onto said balance props. 105

2. In a bed, the combination of: a body; 110 outer legs supporting one side of said body; inner legs pivoted to the floor and to said

body, and wholly supporting the other side of said body with said bed in its usable position; and balance props between said inner legs and the center of gravity of said body.

3. In a bed, the combination of: a body; outer means for supporting the outer edge of said body; inner means for wholly supporting the inner side of said body with said bed in its usable position; and means intermediate said outer and inner means upon which said body may be wholly supported to allow the outer side to be raised for the purpose of standing said body vertically.
4. In a bed, the combination of: a body; outer means for supporting the outer side of said body; inner means for wholly supporting the inner side of said body with said bed in its usable position; and means intermediate said outer and inner means and between said inner means and the center of gravity of said body upon which said body may be wholly supported to allow the outer side to be raised for the purpose of standing said body vertically.

5. In a bed, the combination of: a body; outer supports and inner supports upon which the entire weight of the body is supported with the bed in its usable position; and intermediate supports which may be utilized to support the greater portion of the body's weight during the turning of said body from an intermediate to a vertical position.

6. In a tilting bed, the combination of: a body; a balance prop pivoted to said body at one side of the center of gravity of said body; and means for supporting said body, so arranged that the weight of said body can be lowered to rest on said balance prop preparatory to and during tilting of the bed.

7. In a tilting bed the combination of: a body and a balance prop normally inactive but upon which the weight of said body may be supported preparatory to and during the tilting of the bed.

In testimony whereof, I have hereunto set my hand at Los Angeles, California, this 6th day of December, 1920.

GEORGE FELIX DE GRASSE.
